UNITED STATES PATENT OFFICE.

WILLIAM HARAH BAIRD, OF BURLINGTON, IOWA.

BRUSH.

SPECIFICATION forming part of Letters Patent No. 678,431, dated July 16, 1901.

Application filed August 14, 1900. Serial No. 26,857. (No model.)

To all whom it may concern:

Be it known that I, WILLIAM HARAH BAIRD, a citizen of the United States, residing at Burlington, in the county of Des Moines and State 5 of Iowa, have invented a new and useful Brush, of which the following is a specification.

My present invention relates to improvements in brushes, the object in view being 10 to produce at comparatively small expense a brush particularly designed for dental purposes, formed in a manner to fit the dental arch and constructed of material which will render the brush antiseptic and will permit 15 its use in hot or cold water without danger of deterioration.

A further object of the invention is to construct a brush which will not warp under various conditions of use and the manufacture 20 of which will be facilitated by the employment of a separate bristle-plate in which the bristles are mounted before the plate is placed in the brush.

Further objects of the invention will hereinafter more fully appear as the necessity for their accomplishment is developed in the succeeding description, reference being had to the accompanying drawings for the purpose of more clearly defining the construction and 30 arrangement of the dental brush and of other forms of brushes which are capable of being produced without departing from the spirit of the invention.

In the drawings, Figure 1 is a perspective view of a tooth-brush constructed in accordance with my invention. Fig. 2 is a transverse sectional view on the line 2 2 of Fig. 1. Fig. 3 is a perspective view of the brush-frame detached. Fig. 4 is a perspective view 40 of the tooth-brush looking from the under side and with a number of the bristles removed. Fig. 5 is a view similar to Fig. 1 of a modified form of the invention. Fig. 6 is a perspective view, partly broken away, of a hair-brush constructed in accordance with the invention. Fig. 7 is a perspective view of a clothes-brush. Fig. 8 is a detail perspective view of the wire bead. Fig. 9 is a detail view of the bristle-plate, and Fig. 10 is a similar 50 view of the backing-plate.

Referring to the numerals of reference employed to designate corresponding parts in

the several views, 1 indicates the frame of a tooth-brush stamped from a blank of sheet metal, preferably aluminium, and bent to 55 form a hollow handle 2 and a longitudinally-curved brush-loop 3, having its lower edge 4 turned in and disposed substantially at right angles to the side walls 5 of the loop. In the course of manufacture this brush-frame is 60 formed by first cutting out a suitable blank and next stamping an elongated opening therein, said opening defining the inner edge of the inturned flange 4 of the loop. The handle portion of the blank is then folded over, 65 and the edges are brought together and are soldered along a line disposed at the back of the handle 2. The side walls 5 of the loop are then turned up, as shown in Fig. 3, and the frame is ready for the reception of the several other 70 elements of the brush structure. From the sheet metal is next cut what may be termed the "bristle-plate" 7, conforming substantially to the contour of the head of the brush—that is to say, to the interior dimensions of 75 the side walls 5 thereof—and is punched to form a number of perforations or bristle-sockets 8 for the reception of the tufts of bristles 9. These bristles are inserted in the bristle-plate before the latter is incorporated in 80 the brush structure and are retained against detachment from said plate by means of an insoluble bristle-retaining cement 10, which after the tufts of bristles are passed through the plate is spread over the upper surface or 85 back of the plate to form a binder for the bristles. The bristle-plate 7, with its complement of bristles, is now placed in the brush-frame, with its edges resting upon the plate-supporting flange 4, and is retained in place 90 by a filler 11 of insoluble cement and asbestos combined, which filler is spread over the cement binder of the bristle-plate until the desired thickness or body has been obtained. After the filler has been properly applied it 95 is covered by a backing-plate 12, which fits snugly within the side wall 5 of the head-loop and has a comparatively narrow extended end 13, which projects into the adjacent extremity of the handle. The backing-plate is then 100 pressed firmly in place in order to compress the filling 11 and to form a solid backing for the bristles. Next a wire stiffening-bead 14 is placed upon the backing-plate, with its

ends 15 extended into the handle, and the brush is finally completed by rolling the upper edge of the side wall 5 to form a hollow bead for the reception of the head-loop over 5 the wire bead 14, as best seen in Fig. 6 of the drawings. The edges of the metal are then rubbed down, and the exposed metal surfaces are polished in the manner well understood in the art.

10 In Fig. 6 I have illustrated a modification of the invention which merely comprehends the construction of a hair-brush instead of a tooth-brush, the only difference between this article and the tooth-brush residing in the 15 dimensions and general design. In Fig. 7 I have shown a clothes-brush constructed in accordance with the invention, and in Fig. 5 I have shown a slight modification of the construction shown in the first three figures, inasmuch as I have endeavored to illustrate the manner in which the backing-plate 12 might, if desired, be extended from end to end of the brush in order to constitute a backing for both the head and handle thereof.

25 From the foregoing it will be seen that I have produced an inexpensive, practically indestructible, and exceedingly light brush, the parts of which are secured in a manner to preclude the possibility of their separation when 30 subjected to the action of heat—as, for instance, by immersion in boiling water; but while the present embodiment of my invention appears at this time to be preferable I do not wish to be understood as limiting myself to the constructions illustrated and described, since it is obvious that many variations of design and general arrangement might be effected without departing from the spirit of the invention. I therefore reserve 35 the right to effect such changes, modifications, and variations as may be properly comprehended within the scope of the protection prayed.

What I claim is—

45 1. A brush comprehending a frame-loop having inturned flanges, a bristle-plate carrying bristles and having its edges supported by an inturned flange, the edges of said frame-loop above the bristle-plate being inturned, a 50 backing-plate and a wire bead retained against the backing-plate by one of said inturned flanges.

2. A brush comprising a frame-loop having an inturned flange, a bristle-plate resting upon said flange, a backing-plate disposed be-

hind the bristle-plate, the upper edge of the frame-loop being rolled to form a hollow bead opposed to the backing-plate.

3. A brush comprising a frame-loop having its edges inturned, a bristle-plate and a backing-plate retained by said inturned edges of the frame-loop, and a filler of insoluble cement and asbestos between said plates. 60

4. A brush comprising a frame-loop having its opposite edges inturned, a bristle-plate, a backing-plate and an intermediate insoluble and non-conductive plastic filler all retained between the inturned edges of the frame-loop, and a wire bead located behind the backing-plate and retained within the opposed in-turned edge of the frame-loop. 65

5. A brush comprising a frame-loop and handle, the opposite edges of said frame-loop being inturned, a bristle-plate and a backing-plate disposed between the inturned edges of the frame-loop, said backing-plate being extended into the handle, a filler between the bristle-plate and backing-plate, and a wire bead located within the inturned edge of the frame-loop which is opposed to the backing-plate. 75

6. A brush comprising a handle and a frame-loop, the edges of which latter are inturned, a bristle-plate and a backing-plate having their edges clamped between the inturned edges of the frame-loop, a wire bead retained by one of the inturned edges of the loop, said bead and backing-plate being extended into the handle. 80

7. A brush comprising a frame struck from a single sheet of metal and comprising a hollow handle and a frame-loop having its edges inturned, a bristle-plate and a backing-plate clamped between the inturned edges of the frame-loop, said backing-plate being extended into the hollow handle, a wire bead enclosed by one of the inturned edges of the frame-loop and likewise extended into the handle, a plastic filler intermediate of the bristle-plate and backing-plate, bristles retained in the bristle-plate, and a coating of cement connecting and binding the bristles at the back side of the bristle-plate. 90

In testimony that I claim the foregoing as my own I have hereto affixed my signature in the presence of two witnesses.

WILLIAM HARALD BAIRD.
